Primary Examiner — Janice Hallmark*Assistant Examiner* — Harold E Blackwell, II(74) *Attorney, Agent, or Firm* — D'Ambrosio & Menon, PLLC; Usha Menon(57) **CLAIM**

The ornamental design for a wall mounted overhead tool rack, as shown and described.

DESCRIPTION

FIG. 1 is a top plan view of the wall mounted overhead tool rack;

FIG. 2 is a front elevation view of the wall mounted overhead tool rack thereof;

FIG. 3 is a bottom plan view of the wall mounted overhead tool rack thereof;

FIG. 4 is a left elevation view of the wall mounted overhead tool rack thereof;

FIG. 5 is a right elevation view of the wall mounted overhead tool rack thereof;

FIG. 6 is a front Top isometric view of the wall mounted overhead tool rack thereof; and,

FIG. 7 is a back top isometric view of the wall mounted overhead tool rack thereof showing a representative use. The broken lines in FIG. 7 represent the environment and form no part of the claimed design.

1 Claim, 4 Drawing Sheets(56)
